Veynar*Attorney, Agent, or Firm*—Fitzpatrick, Cella, Harper & Scinto**[73] Assignee: Canon Kabushiki Kaisha, Tokyo, Japan****[57] CLAIM****[**] Term: 14 Years**

The ornamental design for a toner bottle cap for copying machine, as shown and described.

[21] Appl. No.: 44,587**DESCRIPTION****[22] Filed: Sep. 27, 1995****[30] Foreign Application Priority Data**

Mar. 28, 1995 [JP] Japan 7-8427

[52] U.S. Cl. D18/40; D18/43**[58] Field of Search** D18/40, 43, 56; 118/653, 657; 141/1; 206/216, 316, 446, 461, 467; 222/DIG. 1, 166, 240, 325, 541; 355/200, 245, 260, 298

FIG. 1 is a front elevational view of a toner bottle cap for copying machine showing our new design;

FIG. 2 is a rear elevational view thereof;

FIG. 3 is a top plan view thereof;

FIG. 4 is a bottom plan view thereof;

FIG. 5 is a left side elevational view thereof;

FIG. 6 is a right side elevational view thereof; and,

FIG. 7 is a perspective view thereof.
